UNITED STATES PATENT OFFICE.

ADOLPHUS BONZANO, OF PHILADELPHIA, PENNSYLVANIA.

ANTICREEPER FOR RAILS.

No. 890,328.

Specification of Letters Patent.

Patented June 9, 1908.

Application filed August 31, 1907. Serial No. 390,844.

To all whom it may concern:

Be it known that I, ADOLPHUS BONZANO, a citizen of the United States, residing in Philadelphia, Pennsylvania, have invented certain Improvements in Anticreepers for Rails, of which the following is a specification.

My invention relates to certain improvements in means for preventing longitudinal creeping of railway rails due to their tendency to move under the action of passing trains, or to expansion and contraction.

The object of my invention is to provide a simple and effective device for preventing creeping of the rails without directly attaching the rail to a tie or ties but indirectly through a member, which acts both as a strut and tension member held to the rail by a clamp situated midway between two ties. This object I attain in the following manner, reference being had to the accompanying drawings, in which:

Figure 1, is a side view of a rail showing my improved anti-creeping device in position; Fig. 2, is a plan view; Fig. 3, is a transverse section on the line 3—3, Fig. 1; and Fig. 4, is a perspective view of part of the device detached.

A is the rail, B, B are the ties; the rail has the usual head *a* and base flange *b*. Clamped to the base flange, in the present instance between two ties B, B, is a block C, which is preferably serrated at *c* so as to bite into the edge of the flange of the rail and is confined thereto by a bolt D turned up at one end *d* to embrace the flange of the rail opposite to that embraced by the block C, and a bolt passes through an opening in the block and through an opening *e* in the bar E and is confined thereto by a nut *d'* mounted on the threaded portion of the bolt, as illustrated clearly in Fig. 3.

The bar E is preferably made as illustrated in Fig. 4, being formed from a flat blank bent as shown at *e*, *e'*, so that the central portion *E'* is at right angles to the end portions *E*.

The bar can be of any width and thickness desired, preferably about 2½ inches wide and $\frac{5}{8}$ of an inch thick.

The bar E is firmly secured to the ties by screw bolts or spikes *f*, so as to rigidly hold the bar in position. I have shown a screw bolt at each end of the bar, but it will be understood that two or more bolts may be used if desired.

The device is preferably attached at or near the middle of each rail in order to secure equal distances between rail ends when motion occurs from changes in temperature and rolling loads and each end of the bar E is securely fastened to a tie.

One device as described above is sufficient to securely anchor each rail.

By the above described arrangement I am enabled to make a very economical and readily applied anti-creeping device for railroad rails which will act as a strut and tension member, no matter in which direction the rail has a tendency to creep.

This device does not interfere with the tamping of the roadbed and is readily applied or detached when desired.

I claim:

The combination in an anti-creeping device for railway rails, of a rail, two ties, a bar bent to form a central vertical section and horizontal end sections, a block engaging one base flange of the rail between the ties, a hooked bolt engaging the other base flange of the rail and passing through the block and through an opening in the vertical portion of the bar, and means for securing the bar to the ties, substantially as described.

In testimony whereof, I have signed my name to this specification, in the presence of two subscribing witnesses.

ADOLPHUS BONZANO.
